GARDEN WEEDER OR THE LIKE

Albert E. Bruneau, 322½ SW. Front St., Aberdeen, Wash.

Filed June 1, 1960, Ser. No. 60,813

Term of patent 7 years

(Cl. D35—2)

FIGURE 1 is a front perspective view of a garden weeder or the like embodying my new design, a portion of the handle being broken away for convenience of illustration;

I claim:

The ornamental design for a garden weeder or the like, as shown and described.
